ABSTRACT OF THE DISCLOSURE

The present invention overcomes the problem of measuring very small concentrations of substances, such as CO or N₂, with a mass spectrometer in the presence of time fluctuations of the contact potential causing relatively strong fluctuations of the ion current. One of the mixture components, for example CO₂, serves as a standardization component causing measurement peaks which, with two different electron acceleration voltages in an electron beam mass spectrometer, are not appreciably masked by measurement peaks of other substance components. A control signal is provided of magnitude which corresponds to the ratio of the ion currents for the two different electron acceleration voltages and is utilized for controlling at least the smaller of the electron acceleration voltages to main the ratio of the ion currents substantially constant.

The invention relates to a method and arrangement for maintaining constant the effective ionisation energy in the mass spectrometric analysis of mixtures of gaseous substances, with ionisation of the substance mixture by electron bombardment, and measurement of the ion currents of components of the mixture with two differently large electron acceleration voltages, of which at least one lies in the steep commencement region of the ionisation function of the mixture components. The accuracy of the analysis depends essentially on how constant the ionisation conditions remain during the measuring time.

The ionisation probability for a particular kind of molecule is dependent only on the energy of the ionising electrons, at constant temperature. In order to keep this energy constant, it is not sufficient in all cases to stabilise the externally applied electron acceleration voltage, since the electron energy is not exclusively determined by the applied electron acceleration voltage, but additionally is dependent on potentials which cannot readily be dealt with. There are those of the penetration factor of the ion acceleration field in the ionisation zone, and the contact potential which is effective when electrons emerge from the cathode. The latter is at the basis of uncontrollable time fluctuations which are dependent on the surface characteristic of the cathode, and which cause more or less large ion current fluctuations, depending on which point of the ionisation function one uses. The typical course of an ionisation function is to be seen from FIG. 2 of the accompanying drawings.

Above a certain minimum value of the electron energy, ions occur the number of which increases strongly with increasing electron energy, reaches a maximum value and then decreases again. In order to keep the ion current constant and as far as possible independent of fluctuations of the electron energy, one usually works in the region of the maximum of the ionization function, by using an electron acceleration voltage of for example about 100 volt. The possible time alternation of the contact potential of 1 volt maximum then has only a negligible influence on the ion current. There are however special analysis problems in which this manner of excluding the influence

of the contact potential on the ion current cannot be used, since it is required to make use of precisely the characteristic curve of the ionisation function in the steep commencement region for an analytical investigation. An analysis example of this kind is dealt with by J. Cornides in the *Zietschrift für Analytische Chemie*, vol. 171, pages 431—433. It relates to the technically important problem of the analysis of Co—N₂ mixtures, which cannot be simply solved mass spectrometrically in the usual manner, since the two molecular masses are distinguished by only 1/2500 mass units and therefore cannot be separated with simple devices, and because the occurring fragment ion currents are relatively small. Cornides has proposed to solve the problem by measuring the unresolved molecular ion current consisting of ¹²CO¹⁶⁺ ions and ¹⁴N₂⁺ ions at two different electron acceleration voltages U_{e1} and U_{e2}, for which the ratio of the ionisation probability for both molecular kinds is very different. In the extreme case, the lower electron acceleration voltage U_{e1} can be so selected that the electron energy has a value which lies above the ionisation threshold of the one, but below the ionisation threshold of the other kind of molecule. In the practical realisation of this extreme case, allowance in any event has to be made for the fact that the absolute ion current yield in this case is also extremely small. With this method, at least one of the electron acceleration voltages has to be so selected that at least one of the molecular kinds is ionised in the steep commencement region of its ionisation function. In this region time fluctuations of the contact potential cause relatively strong fluctuations of the ion current, which reduce the achievable measuring accuracy, so that very small CO or N₂ concentrations cannot be determined in this manner. The exclusion of these time fluctuations, which are of the order of magnitude of 35 seconds, is the problem which underlies the present invention.

In accordance with the invention, for one of the mixture components (for example CO₂) serving as a standardisation component, the measurement peaks of which, with the two different electron acceleration voltages are not or are not essentially masked by peaks of other substance components, a control magnitude is formed which corresponds to the ratio of the ion currents of the two electron acceleration voltages, and is applied for controlling at least the smaller of the electron acceleration voltages, in such a manner that the ratio of the ion currents remains constant. By this method, not only is the measurement of the ion current of the standardising component possible with the desired accuracy, but also the ion currents of all other components of the mixture can be measured in the steep commencement region of the ionisation function, i.e. with low ionisation voltage. More particularly, also the procedure proposed by Cornides for separation of substances of similar molecular weight, for example N₂ and CO can be successfully performed.

The method of the invention is not only of advantage where it is a question of separation of substance components with similar molecular weight, but has general significance for the mass spectrometric analysis of substance mixtures with low ionisation energy (low voltage mass spectrometry), in which the occurrence of fragmentary ions is known, is reduced.

In order to make the invention clearly understood, reference will now be made to the accompanying drawings which are given by way of example and in which:

FIG. 1 diagrammatically illustrates an arrangement for performing the method of the invention;

FIG. 2 illustrates the variation of an ionisation function;

FIG. 3 is a graph diagram of the commencement region of the ionisation functions for components of a substance mixture to be analysed in the arrangement according to FIG. 1; and

FIG. 4 is a table relating to FIGS. 1 and 2.

The method for maintaining constant the effective ionisation conditions according to the invention is illustrated in the embodiment shown, for the analysis of a substance mixture of CO, N₂, O₂ and CO₂, with the aid of a mass spectrometer which operates with a magnetic sector field for separating the ions, and ionisation of the substance mixture by electron bombardment. In order that no dead time has to be allowed for and in order to be able to form the control circuit as simply as possible, fixed mass setting or constant magnetic field is used, with a plurality of ion interceptors for the ion currents of the various substance components to be measured. The method can of course also be performed with mass spectrometers of a different kind, with a different manner of ion separation.

Only those parts of the sector field mass spectrometer which are essential for understanding the invention are shown in FIG. 1, namely the high vacuum vessel 1, the ion source 2 with a box 4 surrounding the ionisation space 3, the sample inlet 5 to the ionisation chamber, the electrodes 6 and 7 of the electron acceleration device, the 180° deflection magnet 8 and the ion interceptors 9, 10 and 11.

A heated filament electrode 6 forming one of the electrodes of the electron path is connected in the usual way with an emission current control 12, to which also the anode 7 is connected. The box 4 of the ion source 2 is at an ion acceleration potential which is supplied from a high voltage source 13. For producing the desired electron energy, an electron acceleration voltage U_e is placed between the box 4 and the electrode 6 of the ion source. This voltage is supplied by a direct current source 14 with two fixed voltages U₁ and U₂ and a controllable voltage U₃, which is connected with two outputs and a switch 15 for changing over to the two different electron acceleration voltages U_{e1}=U₁+U₃ or U_{e2}=U₂+U₃, U₁ being smaller than U₂, whereby U_{diff.}=U₂-U₁. The change-over is effected by a relay 6 which is controlled by a programme generator 17 in accordance with a programme described further below. The electron acceleration voltage U_{e1} is controlled by the measured ion currents in a manner to be further described below, in such a way that the effective ionisation energy in the ion source 2 is automatically maintained constant at a predetermined value, as long as the voltage U₁ is switched on through the switch 15.

The components of the mixture to be analyzed are ionised in known manner in the ionisation source and are drawn out of the ion source through an ion-optical system not illustrated in the drawing, in the form of a sharply bundled beam into the field of the sector magnet 8. There, according to the magnitude of their mass numbers, they are more or less strongly deflected, as illustrated by broken lines in the drawing, and are separately intercepted by the interceptors 9, 10 and 11 provided at the output, these being arranged in accordance with the track paths. These track paths depend on the mass number of the molecules, the field strength of the deflecting magnet and on the ion energy, which is adjusted by alteration of the ion acceleration voltage at the voltage source 13.

Whereas the CO⁺₂ and O⁺₂ ions separately pass to the interceptors 11 and 10, the CO⁺ and N⁺₂ ions, due to their equally large masses to a first approximation, experience an equally large deflection and pass commonly to the interceptor 9. The relevant ion currents are indicated by i₄₄, i₃₂ and i₂₈, in accordance with the magnitude of the ion masses. These currents are amplified in amplifiers 18, 19 and 20 and after a control procedure which will be subsequently described is performed, they are recorded in chart recording devices 21, 22 and 23.

In order to measure the concentration of the CO and N₂ components of the gas mixture, the ion measurement is performed successively with two differently large ionisation energies, of which one lies in the steep commencement region of the ionisation function of at least one of

the two components and of which the other lies in the maximum region of the ionisation functions. In FIG. 2, an ionisation function, namely the magnitude of the ionisation probability in dependence on the electron energy, is illustrated. The path of such functions is known from measurements.

The two electron acceleration voltages U_{e1} and U_{e2} are so selected that the components of the ion currents i⁺_{N₂} and i⁺_{CO} for the two ionisation energies are very different relative to each other, for the ion current i₂₈ measured for the mass number 28. If by C_{N₂} and C_{CO}, the molar percent proportions of the components N₂ and CO in the gas mixture to be analysed are designated, and by ε'_{N₂} and ε''_{N₂} respectively, the specific indication sensitivities for N₂ with U_{e1} and U_{e2} are designated, with ε'_{CO} and ε''_{CO} the specific indication sensitivities for CO with U_{e1} and U_{e2} respectively are designated, and with

$$\epsilon'_{CO \leftarrow CO_2}$$

and

$$\epsilon''_{CO \leftarrow CO_2}$$

respectively the specific indication sensitivities are designated for CO from CO₂ with U_{e1} and U_{e2} respectively, then the ion currents measured at the ion interceptor 9 can be described by the following equations:

$$(i_{28}) U_{e1} = \epsilon'_{N_2} \cdot C_{N_2} + \epsilon'_{CO} \cdot + \epsilon'_{CO \leftarrow CO_2} \cdot C_{CO_2}$$

$$(i_{28}) U_{e2} = \epsilon''_{N_2} \cdot C_{N_2} + \epsilon''_{CO} \cdot + \epsilon''_{CO \leftarrow CO_2} \cdot C_{CO_2}$$

In these, as abovementioned, the quotients

$$\frac{\epsilon'_{N_2}}{\epsilon'_{CO}}$$

and

$$\frac{\epsilon''_{N_2}}{\epsilon''_{CO}}$$

as far as possible deviate strongly from each other, which is achieved by suitable selection of the electron acceleration voltage U_{e1} and U_{e2}. In the illustrated example (FIGS. 3 and 4) U_{e1}=15.5 volt and U_{e2}=100 volt. The molar proportions C_{N₂}, C_{CO} and C_{CO₂} can then be very easily calculated if the specific indication sensitivities ε are determined by previous standardisation measurements. Preferably, the electron acceleration voltages are so selected that the lower ionisation energy, which is allocated to the ionisation voltage U_{e1}, is smaller than the minimum ionisation energy of the nitrogen molecule and of the proportion of CO₂ at mass 28, but greater however than the minimum ionisation energy of the carbon monoxide molecule, so that the current proportion C_{N₂}·ε'_{N₂} and the current proportion C_{CO₂}·ε''_{CO}

$$\epsilon'_{CO \leftarrow CO_2}$$

in the measured ion current (i₂₈) U_{e1} is equal to zero and this is exclusively based on the component CO. This preferred case is considered as a given case in our example. It is however only practicable if the mass spectrometer used is sufficiently sensitive to supply a sufficiently large ion current only for CO, with the required measurement accuracy.

In order to enable accurate measurement, in each case it is necessary to maintain the ionisation energy accurately constant in the steep commencement region, i.e. with the small electron acceleration voltage U_{e1}=U₁+U₃. This is the case if the ratio of the ion currents measured with the large electron acceleration voltage U_{e2}=U₂+U₃ and with the small electron acceleration voltage U_{e1}=U₁+U₃ is to be maintained constant. In order to achieve this, the mixture component CO₂ is used as standardising component. The concentration of this standardising component does not have to be known, but the standardising component must satisfy the following requirements:

(a) Its molecular peak or another characteristic peak of its mass spectrum must supply an accurately measur-

able ion current with the lower electron acceleration voltage U_{e1} ,

(b) The ion current

$$(i_{44})_{U_{e1}}$$

measured with the low electron acceleration voltage U_{e1} must be essentially smaller than the ion current

$$(i_{44})_{U_{e2}}$$

measured with the large voltage U_{e2} , and the ion current measured with the large voltage must lie in the maximum region of the ionisation function of the standardising component, and

(c) The observed peak with the two voltages must be covered as far as possible exclusively by the standardisation component and not by other components of the mixture.

The control of the electron acceleration voltage U_{e1} must take place in such a manner that for the standardisation component CO_2 , the ratio of the ion currents measured for the mass number 44

$$\frac{(i_{44})_{U_{e2}}}{(i_{44})_{U_{e1}}}$$

remains constant. In order to achieve this, use is made at the output of the amplifier 20 of a precision potentiometer 24 which is so adjusted that the two output voltages U_{11} taken from it with use of the electron acceleration voltage U_{e1} and U_{12} with use of the electron acceleration voltage U_{e2} are equal to each other.

The voltages U_{11} and U_{12} are fed through a changeover relay 25 in the sequence of the changeover of the relay 16, to a servo-amplifier 24 the output of which controls a servo-control 27 for the variable voltage constituent U_3 .

The programme generator 17 operates in such a way that in a first period a control of the voltage U_3 is effected, namely in such a manner that the output voltage U_{11} with $U_{e1}=U_1+U_3$ is equal to the output voltage U_{12} with $U_{e2}=U_2+U_3$. During this compensation period, the relays 16 and 25 are changed over in synchronism, with a frequency of 1 to 10 cycles per second. The changeover frequency must be so high that the fluctuations of the ionisation conditions during the duration of the control procedure, including the measurement connected therewith, are negligibly small. If the measurement is not effected as in the exemplary embodiment with simultaneous interception of the substance component ion currents by separate interceptors, but with transition through the masses, for example by alteration of the magnet current of a deflecting magnet, then transition through the masses has to be effected so rapidly that also the fluctuations of the ionisation conditions are sufficiently small during the transition time.

After this compensation period, the recording of the ion currents i_{28} , i_{32} and i_{44} is effected, firstly with the electron acceleration voltage $U_{e1}=U_1+U_3$ and then with the electron acceleration voltage $U_{e2}=U_2+U_3$. The recording of the ion currents with the two different electron energies is performed when necessary, with changeover of sensitivity at the potentiometers 28 29 and 30, which are change over synchronously with the relays 16 and 25 by a relay 31.

The table in FIG. 4 shows the magnitude of the concentrations of the various mixture components in dependence on the measured ion currents. The constants

$$\epsilon'_{CO_2}, \epsilon''_{CO_2}, \epsilon'_O_2, \epsilon''_O_2, \epsilon'_{CO}, \epsilon''_{CO}, \epsilon'_{CO \leftarrow CO_2} \text{ and } \epsilon''_{CO \leftarrow CO_2}, \epsilon''_{N_2}$$

can be obtained by standardisation measurements. The evaluation of this analysis is accordingly simple. If the ion currents $(i_{44})_{100}$, $(i_{32})_{100}$, $(i_{28})_{100}$, $(i_{28})_{100}$, $(i_{28})_{15.5}$ are recorded, then the desired concentrations are found

$$C_{CO_2} = \frac{(i_{44})_{100}}{\epsilon''_{CO_2}}$$

$$C_{O_2} = \frac{(i_{32})_{100}}{\epsilon''_{O_2}}$$

$$C_{CO} = \frac{(i_{28})_{100} - C_{N_2} \cdot \epsilon''_{N_2} - \epsilon'_{CO \leftarrow CO_2} \cdot C_{CO_2}}{\epsilon''_{CO}}$$

$$C_{N_2} = \frac{(i_{28})_{100} - \frac{\epsilon''_{CO}}{\epsilon'_{CO}} \cdot (i_{28})_{15.5} - \frac{\epsilon''_{CO \leftarrow CO_2}}{\epsilon''_{CO_2}} \cdot (i_{44})_{100}}{\epsilon''_{N_2}}$$

By introducing the expressions for C_{N_2} and C_{CO_2} into the expression for C_{CO} , after rearrangement one receives:

$$C_{CO} = \frac{(i_{28})_{15.5}}{\epsilon'_{CO}}$$

In the described manner, the effective ionisation energy can thus be maintained constant also in the steeply rising commencement region of the ionisation functions and analyses may be performed selectively with normal and with low ionisation voltages.

Many modifications are possible. As standardising substance, a component present in the mixture may be used, which satisfies the above given requirements. If such a component is not present, then a suitable standardising substance can be added. In the analysis of converter waste gases and blastfurnace gases, the problem exists of continuously analysing a gas mixture which is composed of the components N_2 , CO_2 , CO and O_2 , the component CO_2 being present in sufficient concentration so that for this mixture the preliminary requirements that are placed on the standardising substance are satisfied. With compensation of the electron acceleration voltage, the procedure can also be such that the above described relative value for which a suitable value can be derived from the ionisation function of the standardising component used for the control, gives the fixed ratio of the measuring times the two electron acceleration voltages. The entire changeover period is in this case not divided into two equal parts, but is divided into the unequal measurement intervals t_1 and t_2 . During the measurement interval t_1 , the electron acceleration voltage $U_{e1}=U_1+U_3$ is switched in and during the measurement interval t_2 the electron acceleration voltage $U_{e2}=U_2+U_3$ is switched in. Similarly as above described, with this method, U_3 is controlled so that the commencement voltages U_{a1} and U_{a2} at the ion current amplifier for the standardising component, multiplied by the relevant measurement time interval t_1 and t_2 gives the same product $U_{a1} \cdot t_1 = U_{a2} \cdot t_2$.

This kind of control is more expensive to provide but it has however, the principal advantage that the measurement time for the low ion currents is essentially larger with the smaller ion acceleration voltage, and in the border case is twice as large as with the control method with equal measurement time intervals described above in detail. This extension of the measurement time for the small ion currents naturally favours the measurement accuracy.

In the embodiments described, the larger electron acceleration voltage U_{e2} is subjected to the same increase or reduction as the smaller voltage U_{e1} . It would lead to essentially the same result if only the smaller voltage U_{e1} were controlled, provided that the larger voltage U_{e2} lies in the maximum region of the ionisation functions, where the related alterations of the electron acceleration voltages would not cause any noticeable alteration of the ion currents.

What we claim is:

1. A method for maintaining constant the effective ionisation energy in the mass spectrometric analysis of mixtures of substances, with ionisation of the substance mixture in the gaseous condition by electron bombard-

ment, and measurement of the ion currents of mixture components with two differently large electron acceleration voltages, of which at least one lies in the steep commencement region of the ionisation functions of the mixture components, wherein for a component serving as standardising component, the measurement peaks of which with the two electron acceleration voltages are not or are not essentially masked by peaks of other components of the mixture, which method includes the steps of selectively establishing said two differently large electron acceleration voltages, providing a control signal magnitude representative of the ratio of said ion currents with both said electron acceleration voltages and controlling at least the smaller of said electron acceleration voltages with said control signal so as to maintain said ratio of the ion currents substantially constant.

2. A method as claimed in claim 1, wherein alteration between both electron acceleration voltages is produced by switching over between two fixedly provided partial voltages which differ by a fixed difference voltage and controlling at least said smaller voltage so that the ratio of the two allocated ion current values for the standardising component has the said prescribed substantially constant magnitude.

3. A method as claimed in claim 1, wherein the predetermined magnitude of the ion current relationship is established by adjusting a voltage divider at the output of the mass spectrometer so that the ratio of the partial voltage taken off at the voltage divider to the total voltage thereon corresponds to the predetermined ratio of the lower ion current with smaller electron energy to the larger ion current with greater electron energy, and further including the step of controlling at least the absolute value of the smaller electron acceleration voltage so that the said total voltage measured with the lower electron energy is equal to the said partial voltage taken off at the voltage divider, for the larger electron energy.

4. A method as claimed in claim 1, wherein the predetermined magnitude of the ion current ratio is set by adjusting a time generator for two unequally long measurement intervals for the two electron acceleration voltages, respectively, so that the ratio of the lengths of the smaller interval, during which the larger ion current is measured with the larger electron energy, relative to the length of the larger interval, during which the smaller ion current is measured with the smaller electron energy, corresponds to the predetermined ratio of the smaller ion current to the larger ion current, and controlling at least the absolute value of the smaller electron acceleration voltage so that the product of smaller ion current with larger measurement interval length is substantially equal to the product of larger ion current with smaller measurement interval length.

5. A method as claimed in claim 1 which method includes mass spectrometrically analyzing substance mixtures with low ionisation energy, in the steep commencement region of the ionisation function, and suppressing fragmentary ions.

6. A method as claimed in any one of claims 1 to 4 which method includes mass spectrometrically analyzing substance mixtures with components the mass spectra of which contain the strongest ion contributions at equal

mass numbers, to a first approximation, the ionisation energies of which are however noticeably different.

7. A method as claimed in claim 6, wherein the smaller ionisation energy lies in the steep commencement region of the ionisation functions of the standardising component, and also one of the mixture components to be measured, but below the minimum ionisation energy of the other mixture component or components to be measured.

10 8. Apparatus for practicing the method claimed in claim 1, comprising a mass spectrometer with an electron impact ion source, an electron acceleration voltage source which is switchable to said two differently large acceleration voltages and having a fine adjustment device for at least the smaller of said acceleration voltages.

15 9. An arrangement as claimed in claim 8, wherein said fine adjustment device comprises a precision potentiometer connected to an interceptor system of the mass spectrometer.

10 10. An arrangement as claimed in claim 9, wherein said precision potentiometer is coupled through a change-over switch to means comprising a servo-device, for automatic fine adjustment of the acceleration voltage source.

20 11. An arrangement as claimed in claim 8 and further comprising, program controller means for in each individual mass spectrometric measurement performing in the comparison interval the adjustment of the acceleration voltages to the prescribed ion current ratio for the standardising component and in a following measurement interval initiates the indication or the recording of the mass spectrum.

25 12. An arrangement as claimed in claim 11, and further comprising a changeover switch for controlling the sensitivity of the mass recording, which operates in sequence with the changeover of the acceleration voltage.

30 13. An arrangement as claimed in claim 8, wherein the precision potentiometer at which the ion current ratio of the standardising component determined by the acceleration voltages is adjustable, is connected to a changeover switch coupled with the acceleration voltage changeover switch, which for the smaller acceleration voltage switches on the entire voltage at the potentiometer and for the larger acceleration voltage switches on the voltage lying at the slider of the potentiometer.

35 14. An arrangement as claimed in claim 9, wherein said precision potentiometer is connected with an interceptor provided solely for the standardising component.

40 15. An arrangement as claimed in claim 14, and further comprising means for switching the mass spectrometer during the compensation interval for recording of the ions of the standardising component, onto the interceptor connected to said precision potentiometer.
